(57) **CLAIM**

The ornamental design for a game controller, as shown and described.

DESCRIPTION

FIG. 1 is a top plan view of a game controller showing my new design;

FIG. 2 is a top plan view of a second embodiment of a game controller, with the contrasting transparent surface to the controls and the surface therein;

FIG. 3 is a third embodiment of a game controller, with the contrasting surface to the body of a game controller;

FIG. 4 is a fourth embodiment of a game controller, with another contrasting surface to the body of a game controller;

FIG. 5 is a top and front perspective view of FIG. 1;

FIG. 6 is a rear perspective view of FIG. 1;

FIG. 7 is a top and rear perspective view of FIG. 1, with a battery compartment being separated from the body of a game controller;

FIG. 8 is a bottom plan view of FIG. 1;

FIG. 9 is a bottom plan view of FIG. 1, with battery compartment being removed from the body of a game controller; and, FIG. 10 is a rear view of FIG. 9.

The broken lines of the battery in FIG. 7 are for illustrative purpose and form no part of the claimed design.
